UNITED STATES PATENT OFFICE

HARRY C. DREIBUSS, OF ST. LOUIS, MISSOURI, ASSIGNOR, BY MESNE ASSIGNMENTS, TO SCULLIN STEEL CO., OF ST. LOUIS, MISSOURI, A CORPORATION OF DELAWARE

SIDE FRAME

Application filed February 11, 1926. Serial No. 87,541.

The present invention relates to improvements in side frames.

More particularly the present invention relates to the side frames of the trucks of railway cars and has for one of its objects the provision of a construction of side frame which will improve the sturdiness thereof over prior practice.

A further object is to provide a cast side frame which will not only have improved sturdiness, but which will simplify the matter of casting.

A further object is to provide a side frame in which the lines of forces in the compression and tension members will intersect at as low a level as possible.

Further objects will appear as the description proceeds.

Referring to the drawings—

20 Figure 1 is a view in side elevation of one end portion of a side frame embodying the principles of the present invention;

Figure 2 is a top plan view of the structure shown in Figure 1;

25 Figure 3 is a fragmentary view taken in the direction of the arrows 3—3 of Figure 1;

Figure 4 is a sectional view taken along the plane indicated by the arrows 4—4 of Figure 2;

30 Figure 5 is a sectional view taken along the plane indicated by the arrows 5—5 of Figure 2;

Figure 6 is a view in end elevation of the structure shown in Figures 1 to 5, inclusive;

35 Figure 7 is a view similar to Figure 1, but illustrating a modified construction;

Figure 8 is a top plan view of the structure shown in Figure 7;

40 Figures 9 and 10 illustrate modifications of the structure shown in the preceding figures; and

45 Figures 11, 12 and 13 are sectional views taken along the planes indicated by the arrows 11—11, 12—12 and 13—13, respectively, of Figure 1.

50 Referring first to Figures 1 to 5, inclusive, the numeral 15 indicates a side frame, each end of which side frame includes the tension member 16 and the compression member 17.

Said tension and compression members 16 and 17 are connected together at the corresponding end portion 18 of the side frame, which end portion 18, in the illustrated embodiment of the present invention, has 55 formed integral therewith the journal box 19.

Though an integral journal box is illustrated in the drawings, it will be clear as the description proceeds that many features of the invention are not limited to integral journal boxes, but are of broader application. The journal box 19 is bevelled at its two upper side portions, as clearly illustrated in the drawings, the bevelled portions 60 being indicated by the numerals 19'—19'. According to the disclosure of Figures 1 to 6, inclusive, said bevelled portions extend from the plane indicated by the line 20 to the plane indicated by the line 21 (Fig. 2), 70 though the present invention contemplates structure in which the bevelled portions extend entirely across the journal box from the plane 21 to substantially the other extremity of the journal box, as indicated by 75 shading in Figure 8. By reason of the bevelled construction referred to, not only are sharp corners avoided and the amount of metal reduced, but furthermore the beam action over the journal box is shortened and 80 a more rigid and stronger design with a more uniform section of metal is provided.

The bevelled structure at the two sides of the journal box, as shown, for example, in Figures 4 and 5, has the further advantage 85 that in casting it is not necessary to provide right and left-hand cores. Inasmuch as the upper outer corner is made the same as the upper inner corner, identical cores may be used in casting, thereby simplifying the casting operation. The bevelled construction at the two sides of the journal box has the further decided advantage of improved 90 rigidity. By reason of the bevelling either substantially the length of the box on the inner and outer edges, or by reason of the bevelling between the planes 20 and 21 (Fig. 2), a truncated gable construction is provided having improved stiffness over a journal box having a flat top from side to 95 100

side. Accompanying this advantage is, of course, the saving of metal.

In order to explain the advantages of the present invention relative to the lowering of the point of intersections of the neutral axes of the tension and compression members 16 and 17, reference is made to Figures 11, 12 and 13, which show cross sections taken along the planes indicated by the arrows 11—11, 12—12 and 13—13, respectively, of said tension and compression members, (see Fig. 1). Referring to Figures 11 and 12, it will be noted that the tension member 16 has a cross section substantially in the form of a U the legs of which member are provided with the in-turned flanges 22 as well as the outturned flanges 23. The compression member 17 is provided with the outturned flanges 23. The neutral axes of the tension member 16 and the compression member 17 are indicated by the lines 24 and 25, respectively. By reason of the described cross sectional shapes of said compression and tension members, and by reason of the bevelled construction at the upper inside corner of the journal box, said neutral axes 24 and 25 are brought to a point of intersection substantially in the vertical central plane of the journal box 19 at a relatively low level.

As will be noted from an inspection of Figures 1 and 5, the web of the channel comprising the tension member 16 is in substantial alignment with the adjacent bevelled portion 19' of the roof of the corresponding journal box, whereby the metal of tension member 16 is well adapted to transmit the stresses. Said web of the tension member 16, it will be noted, slopes substantially from the inner sides of the wedge or brass lugs 19"—19" between the flanges of the corresponding compression and tension members. By reason of the coordination of the journal box having bevelled edges referred to and the tension and compression members as described, the necessary height of the frame is reduced, and at the same time the metal of the journal box is located in line with the forces, producing the most direct action possible. Beam action over the journal box is therefore minimized, accomplishing improved sturdiness over prior practice, with a reduction in metal and a reduction of tendency to crack. The angular arrangement between the roof of each journal box and the inner side wall thereof outwardly of the tension member is such that the roof of the journal box meets said inner side wall at substantially right angles. Intermediate of the flanges of the tension member, however, the angular arrangement above referred to is maintained and this extends back to the usual dust guard well. The same arrangement is followed at the outer corner of the roof or outer side wall of the

box, so that the journal box cores for the right and left sides thereof may be made similar.

The junction of the tension member 16 to the journal box 19 is reinforced by the web 26 and by the laterally extending strengthening ribs of webs 26^a. The web 26 has a strengthening rib or web at its lower edge, as indicated by the numeral 26^b. Said rib 26^b has considerable width at its central portion, as shown in Figure 3, to resist buckling. This rib or web 26^b decreases in width and dies down to the original thickness of the web at the ends. The particular structure described is advantageous from the foundry standpoint to prevent cracking, and is important from a design standpoint inasmuch as it provides improved sturdiness.

Referring now to Figure 7, a modified structure is shown in which webs 29—29 are provided in alignment with the inner wall of the tension member 16. Said webs 29—29, together with said inner wall of the tension member 16, extend from the lower edge of the bolster opening 30 to the top of the compression member. This structure is beneficial in transferring stresses, and also prevents excessive buckling. In the construction shown in Figure 7, the webs 26, 26^a, and 26^b have been eliminated.

Figures 9 and 10 illustrate a construction in which a rib or web 31 is provided extending from the inner wall of the compression member 17 to the journal box 19. Said rib or web is of material benefit in strengthening the side frame, prevents excessive buckling at this particular point, and also acts to tie the journal box to said side frame. By the use of the rib or web 31, the webs or ribs 26—26^a may be eliminated.

The structure illustrated has the decided advantage that the casting operation is simplified, the weight of metal is minimized, and at the same time sturdiness is improved over prior structures.

Though certain preferred embodiments of the present invention have been described in detail, such embodiments are to be considered only as illustrative and not in a limiting sense. Many modifications will occur to those skilled in the art. It is intended to cover all such modifications that fall within the scope of the appended claims.

What is claimed is—

1. A side frame comprising a bolster receiving portion, a compression member connected to the upper part of said bolster receiving portion, a tension member connected to the lower part of said bolster receiving portion, said tension and compression members being disposed in angular relationship with each other and being connected together at their outer ends, a journal box joined to said tension and compression members adjacent to the point of junction of said

members, said tension and compression members comprising channel sections having their neutral axes disposed at a relatively low level, which neutral axes intersect substantially at the vertical central plane of said journal box, said journal box and tension member being provided with a reinforcing web therebetween, the lower portion of said web being provided with a rib of greater width at its mid portion than at its end portions.

2. A side frame having a compression member, a tension member, a journal box integral with said tension and compression members, said tension member comprising a channel section having its web lowermost, said journal box and tension member being provided with a reinforcing web therebetween, the lower portion of said web being provided with a rib of greater width at its mid portion than at its end portions.

3. A side frame comprising a compression member, a tension member and a journal box integral therewith, said journal box and tension member being provided with a reinforcing web therebetween, the lower portion of said web being provided with a rib of greater width at its mid portion than at its end portions.

30 Signed at St. Louis, Mo., this eighth day of February, 1926.

HARRY C. DREIBUSS.
